UNITED STATES PATENT OFFICE.

BURTON W. HILL, OF SOMERVILLE, MASSACHUSETTS.

STEAM-TRAP

SPECIFICATION forming part of Letters Patent No. 604,860, dated May 31, 1898.

Application filed May 18, 1896. Renewed November 11, 1897. Serial No. 658,203. (No model.)

To all whom it may concern:

Be it known that I, BURTON W. HILL, of Somerville, in the county of Middlesex and State of Massachusetts, have invented certain new and useful Improvements in Steam-Traps, of which the following is a specification.

This invention relates to steam-traps of the type illustrated in my Patent No. 550,886, dated December 3, 1895, the object of which is to receive the water of condensation from a steam-heating system and return said water to the boiler or source of steam-supply.

The particular object of this present invention is to provide an improved device of this character in which a vacuum is created in the chamber for receiving the water of condensation, in order that said water may be forced into said chamber more readily, partly due to the pressure of steam behind it, without regard to the relative elevation of the trap and heating system.

To these ends the invention consists in the construction and combination of parts, substantially as hereinafter described and claimed.

In the accompanying drawings, Figure 1 represents a perspective view of a steam-trap embodying my improvements. Fig. 2 represents a side elevation of the same, looking in the direction of the arrow in Fig. 1. Fig. 3 represents a sectional plan view on the line 3-3 of Fig. 2 and looking in the direction of the arrow in said figure. Fig. 4 is an enlarged sectional detail view on the line 4-4 of Fig. 3. Fig. 5 is a section on line 5-5 of Fig. 4, looking in the direction of the arrow 2. Fig. 6 is a section on line 6-6 of Fig. 4, looking in the direction of the arrow 3. Fig. 7 is a section on line 7-7 of Fig. 4, looking in the direction of the arrow 4. Fig. 8 is a section on line 8-8 of Fig. 3. Fig. 9 is an enlarged sectional detail view of the valve.

Similar letters of reference indicate the same parts throughout the several views.

a represents a chamber of suitable form, preferably such as the chamber *d* in the patent above referred to. This chamber *a* is connected by a short pipe with the hollow shaft *b*, journaled in bearings *c*, formed upon a suitable supporting-frame, which in the present instance is located upon the boiler,

the frame and trap being above the level of the boiler. The chamber is normally maintained at a suitable angle by means of a weight *b'*, adjustably secured to a rod projecting from the shaft. The shaft to which the chamber is attached is provided with a pipe or passage *d*, which communicates with the chamber *a*, as shown in Fig. 3, said passage being connected with a pipe *e* by a suitable expansion-joint *e'*, said pipe *e* being connected with branch pipes *f* and *f'*, the pipe *f* leading to the boiler and the pipe *f'* being connected with the system to be drained. The pipes *f* and *f'* are provided with check-valves *g* and *g'*, the object of which is to prevent the passage of water in the direction of the reverse of the arrows shown in Fig. 1 adjacent to said pipes *f* and *f'*. The tubular shaft *b* is also provided with a passage *h*, (see Figs. 3 and 4,) which passage connects with the interior of a valve casing or chamber *h*, said casing being rigidly secured to the shaft, so as to turn therewith. This valve-casing and its contained parts are somewhat of the type shown in my application Serial No. 576,515, filed January 23, 1896.

A pipe *h* leads from the valve-casing to the live-steam-supply pipe *h*', from which steam is admitted into the chamber *a* through the valve casing and passage *h* and through a pipe *h*'' which connects the passage *h* with the upper end of the chamber *a*, as shown in Figs. 1 and 3.

The construction of the valve mechanism is illustrated in Figs. 4 to 7, inclusive, particularly Fig. 4, in which it will be seen that the casing *h* is loosely mounted upon the pipe *h*'' which is stationary, the inner end of said pipe *h*'' being provided with a flange *i*, carrying two guide-pins *i'* and *i''*, which extend through openings in a disk *j*. Said disk is provided with a stem *i'*, having a steep-pitched screw-thread *j'*, which engages with internal threads of a sleeve *i''*, having flanges *i'''* and *i''''*, adapted to fit and reciprocate in the valve-casing. These flanges are provided with suitable openings to permit of the passage of water. This sleeve is prevented from rotating and may be adjusted longitudinally of the valve-casing by means of a screw *i'*, the threaded portion of which fits partly in a groove in the valve-casing and partly in the edge of the flange *i*, as shown in Figs. 4 and 5.

The disk i^3 is formed with a concave face, to which is fitted a disk i^3 , held thereon by means of a suitable flange i^6 , which projects inward over an annular shoulder of the disk i^3 . The face of the disk i^3 is recessed to receive a packing-washer or disk i^1 , said disk constituting the valve proper, adapted to fit the seat j , formed on the inner end of the pipe h^3 .

10 The chamber a is provided with a suitable gage l and with an air-vent l' . (See Fig. 2.) k represents a standard or stop adapted to limit the downward movement of the chamber a , and m represents a runway carried by the shaft b and supporting a weight m' , the object of which is to hold the chamber and the shaft in either of its extremes of position until the chamber a is entirely filled or emptied.

15 The operation of my improved trap is as follows: The water of condensation from the system to be drained enters the pipe f' and passes in the direction of the arrow marked thereon in Figs. 1 and 2 into the pipe e , by which pipe the water is conducted to the chamber a , the vent l' being opened, if necessary, at the beginning of the operation. This vent, if opened at all, is to provide for the escape of air at the first operation, after which it is closed.

20 The chamber a is closed against the admission or access of air in order to provide for the formation of a vacuum as above described. When the water has accumulated in the chamber a until its weight is sufficient to overcome that of the weights b' and m' , the chamber will descend until it comes in contact with the stop k , the ball-weight m' then rolling to the position indicated by dotted lines in Fig. 2. This movement of the chamber and of the shaft b imparts a rotary movement to the valve-casing h^2 and the sleeve i^6 , this movement of the sleeve around the stem i^4 , which is prevented from turning by means of the pins i^5 , resulting in the lifting of the valve from

25 the seat j . This allows the live steam from the boiler to enter the upper end of the chamber a by means of the pipe h^3 , the pressure of the steam then causing the water to flow out of the chamber a and through the passages d and e to and through the pipe f' and to the boiler, the check-valve g yielding to permit of this passage of the water, but preventing any backflow. It will be understood that the check-valve g serves to prevent any backflow

30 of steam or water of condensation through the pipe f' . As soon as the chamber a has been emptied of its contents the weight b' causes it to return to its upper position and close the valve by the reverse of the operation above described. Steam remains in the chamber a , which is exposed to the atmosphere, and gradually cools sufficiently to condense the

steam therein and form a vacuum, resulting in aiding the passage of water of condensation from the heating system into said chamber. 65

I claim—

1. A steam-trap comprising in its construction a shaft mounted to turn in bearings and provided with a longitudinal passage in each end, branch pipes connected with one end thereof, one of the branch pipes being adapted to be connected to the system to be drained and the other to the boiler, a chamber rigidly connected with the said shaft to turn therewith and adapted to receive water from one of said branch pipes and discharge it through the other, a counterbalance for the chamber, a live-steam-supply pipe connecting the upper portion of the chamber with the passage at the other end of the shaft, and a valve located within said shaft and operated by the movements of the chamber to admit steam to the chamber and to cut it off therefrom, whereby a vacuum may be formed in the chamber after cutting off the steam, so as to facilitate the entrance of water to the chamber from the system to be drained. 75

2. In a device of the character specified, the combination with the pipes b and h mounted in bearings, the chamber a connected at its lower end with the pipe b and adapted to turn therewith and with the pipe h , the pipe h^3 connecting the pipe h with the upper portion of the chamber, the pipe h^3 for live steam and having its end provided with a valve-seat, and a valve operated toward and from the said seat by the oscillation of the pipe h , the said valve being movable in the direction of the axis of said pipe. 80

3. In a device of the character specified, the combination with the stationary pipe h^3 having a valve-seat and the guides i^5 , the casing h^2 mounted to rotate on the pipe h^3 , the valve having the threaded stem i^4 and fitted to the said guides, and the threaded sleeve i^6 connected to rotate with the casing h^2 . 85

4. In a device of the character specified, the combination with the stationary pipe h^3 having a valve-seat and the guides i^5 , the casing h^2 mounted to rotate on the pipe h^3 , the valve having the threaded stem i^4 and fitted to the said guides, the threaded sleeve i^6 having the flanges i^7 provided with fluid-passages, and an adjusting-screw i^8 passing through the casing and engaging with a portion of one of the flanges, substantially as described. 95

In testimony whereof I have signed my name to this specification, in the presence of two subscribing witnesses, this 13th day of May, A. D. 1896.

BURTON W. HILL.
